Attorney

UNITED STATES PATENT OFFICE.

ROYAL E. HENDRICKS, OF SAN FRANCISCO, CALIFORNIA.

ELECTRIC SCRUBBING MACHINE.

Application filed February 25, 1926. Serial No. 90,508.

This invention relates to electric machines for scrubbing or polishing of floors by means of revolving brushes, and the objects of the invention are to provide such a machine which will be portable in the manner of a vacuum cleaner and which will effectually polish and scrub floors, particularly marble and tile floors with water and soap while retaining the water within the confines 5 of the machine so that mopping up will be avoided and the floor will be clean and substantially free from water after the machine has passed over it.

In the drawings accompanying this application I show one embodiment of my invention tho it is to be understood that any variations of construction as fall within the spirit of the invention are intended to be covered in my appended claims:

20 The drawings show in Figure 1 a side elevation of my machine with a portion of its side wall broken away to show its interior mechanism, in Figure 2 a plan view of Figure 1 with handle omitted, and in Figure 3 25 an enlarged sectional detail of the outer rubber sealing strip which extends clear around the machine.

In further detail the machine comprises a rectangular casing 1 closed on top and sides 30 and open at the bottom.

This casing is preferably formed of sheet metal and has an outwardly projecting flange 2 at its lower edge over which is sprung a heavy soft rubber grooved ring or 35 endless band 3, as best shown in Figure 3, and which band is adapted to carry a part of the weight of the machine and form a flexible sealing edge against the floor.

Supporting the major part of the weight 40 however are four rollers 4 preferably ball bearing and shod each with a heavy rubber tire.

At the forward end of the machine is mounted a cylindrical revolving brush 5. 45 This brush is of wire for scrubbing tile floors, but is interchangeable with other brushes for polishing by simply removing the pin 6 by which it is secured to a shaft 7 carried in bearings (not shown) in the sides 50 of the machine, and whereupon the shaft may be withdrawn.

The brush is arranged to bear against the floor and is driven in the direction indicated by the arrow through means of an electric

motor 9 belted at 10 to a pulley 11 secured to one end of the brush shaft 7.

55 The terminals 12 of the motor are connected to a suitable electric socket cord in operation and to manipulate the machine a handle 13 is provided which is pivotally yoked at 14 to the sides of the machine 60 casing.

Water, or soapy water, is fed to the revolving brush from a reservoir tank 15 carried on the handle. This tank is a long cylinder with a tubular sleeve 16 extending 65 thorough it so that it may be slipped over the handle as shown and secured by any suitable means such as a removable pin 17.

The reservoir tank 15 is provided at its upper end with a filling cap 18 and at its 70 lower end with an outlet valve 19 from which extends a rubber hose 20 to the forward end of the machine where it connects by means of a union 21 to an L 22 extending into the casing to a transverse pipe 23 75 capped at both ends and perforated along its length so as to drip water to the revolving brush 5 upon opening the valve 19.

An auxiliary handle 30 is secured to the tank 15 for one hand of the operator while 80 the other holds the extreme end of the main handle 13, and to conveniently operate the valve for control of the water to the brush a pivoted spring actuated grip 31 is provided 85 on the handle 30 connected by a rod 22 to the valve so that the valve will always be under control and the valve will always shut off when the grip is released.

In revolving at a high speed against the floor the brush will of course throw water 90 behind it and to control this water a baffle plate 23 is positioned within the casing so as to guide the thrown water over a slanted guard wall 24 to fall into an open tray or drawer 25.

This drawer 25 is slidably supported for 95 rearward removal from the casing and retained in place by a latch 26, so that upon releasing the latch the tray may be taken out and emptied as occasion requires.

To the forward side of the slanted wall 24 100 is secured a soft rubber squeegee sheet 27 held in place by screws and thumb nuts 28 through slots 29 so that it may easily be adjusted or replaced.

105 This squeegee extends the full width of the casing inside and is arranged to yieldingly

press against the floor and acts as a shovel for the water in which the brush is operating and which is thrown up over its face into the tray.

5 6. In operation the soft rubber strip 3 forms a perfect seal against the floor to retain a pool of water within the casing while the squeegee by its cleaning or scraping action insures a clean floor free from pools of water after the machine has passed over it.

Also it should be observed, that while the machine is operating the water forms a freely skidding surface against the soft rubber edge 3 so that the machine turns in every 15 direction with greatest ease.

15 20. The rubber edge 3 being an endless band symmetrical from the groove to both edges may be reversed upon the flange 2 and thereby provide a new edge if it becomes badly worn or cut.

I claim:

1. In an electric scrubbing machine of the character described, a casing closed at the sides and open at its under side, means with- 25 in the casing for scrubbing the floor comprising a revolving cylindrical brush extending across the casing, means for feeding water to the brush, an upwardly and rearwardly slanted guard plate secured across the casing at the rear of the brush, a rubber squeegee strip adjustably mounted on said plate, and

a rearwardly slidable water receiving tray adapted to slide with its forward edge under the upper edge of said guard plate.

2. In an electric scrubbing machine of the 35 character described, a casing closed at the sides and open at its under side, and provided with a horizontally and outwardly extending flange at the lower edge thereof, means within the casing for scrubbing the 40 floor, and a soft rubber edge on the casing substantially sealing the same to the floor, said edge being a grooved rubber band engag- 45 ing in its groove said outwardly extending flange.

3. In an electric scrubbing machine of the character described, a casing closed at the sides and open at its under side, means within the casing for scrubbing the floor, a handle on the machine, means for supplying water 50 to the brush including a cylindrical tank provided with a tube extending axially therethrough, said handle extending through said tube and a pipe leading from the tank to the brush, a handle on said tank cooperating 55 with the first mentioned handle for an operator's guidance of the machine, a valve on said pipe provided with an extended control mounted adjacent the handle on the tank whereby the control may be operated by a 60 hand holding said handle.

ROYAL E. HENDRICKS.
